UNITED STATES PATENT OFFICE.

FREDERICK BOCKELMAN, OF NEW YORK, N. Y.

DESIGN FOR A SHOWER-BATH BODY.

43,664.

Specification for Design.

Patented Mar. 4, 1913.

Application filed January 22, 1913. Serial No. 743,670. Term of patent 14 years.

To all whom it may concern:

Be it known that I, FREDERICK BOCKELMAN, a citizen of the United States, residing at the city of New York, borough of Manhattan, in the county and State of New York, have invented a new, original, and ornamental Design for a Shower-Bath Body, of which the following is a specification, reference being had to the accompanying drawings, forming part thereof, in which—

Figure 1 is a front elevation; and Fig. 2 is a rear elevation.

I claim:

The ornamental design for a shower bath body, as shown.

FREDERICK BOCKELMAN.
